UNITED STATES PATENT OFFICE.

REUBEN H. EVES, OF SPOKANE, WASHINGTON.

IRRIGATING APPARATUS.

Application filed October 10, 1927. Serial No. 225,297.

This invention aims to provide novel means whereby water can be distributed evenly from a flume, for irrigation purposes, it being possible to open and close the flume quickly.

It is within the province of the disclosure to improve generally and to enhance the utility of devices of that type to which the invention appertains.

With the above and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the drawings:

Figure 1 shows in longitudinal section, a device constructed in accordance with the invention, parts being in elevation;

Figure 2 is a top plan;

Figure 3 is a cross section on the line 3—3 of Figure 1.

The numeral 1 marks a flume including a bottom 2 and sides 3. The bottom 2 of the flume 1 is supplied with spaced openings 4 which are distributed over the bottom of the flume as closely together as may be considered expedient, desirable, or necessary. Flat gates 5 are slidably mounted on the bottom 2, between the sides 3, and are provided with openings 6 adapted to register with the openings 4 in the bottom 2. Any desired means may be provided for holding down the gates 5 on the bottom 2. If desired, guides 7 may be mounted on the sides 3, the edges of the gates 5 being slidably received beneath the guides 7. The guides 7 at the respective sides of the flume 1 are connected by stops 8 against which the gates 5 abut at their inner ends when the gates are closed: that is, when the gates are so arranged that the openings 6 in the gates do not register with the openings 4 in the bottom 2. The stops 8 are provided with flanges 9 which overhang the ends of the gates 5, to aid in preventing leakage, when the gates are closed as shown in Figure 1.

The open imperforate portion 10 of the bottom 2 lies between the stops 8, meaning by the word "open" that the part 10 of the bottom is not covered by gates. On the part 10 of the bottom is placed a standard 11

which may have a lateral foot 12 connected by securing elements 14 with the bottom of the flume. The standard 11 has a segment 15 provided with seats 25 and 26.

A lever 16 is fulcrumed intermediate its ends, as at 17, upon the standard 11, the lever being provided with a latch mechanism 18 under the control of an operator, and adapted to be engaged in either of the seats 25—26. The inner end of a rigid link 19 is pivotally connected, as shown at 20, with the lever 16, at a point below the fulcrum 17. The inner end of a rigid link 21 is pivotally connected, as shown at 2, with the lever 16, at a point 70 about the fulcrum 17. The links 21 and 19 extend in opposite directions, and are pivotally mounted at their outer ends, as shown at 23, in anchors 24 which are secured to the gates 5.

When the lever 16 is in the solid line position of Figure 1, the links 19 and 21 draw the gates 5 against the stops 8, the openings 6 in the gates being out of registration with the openings 4 in the bottom 2. The water, 80 consequently, cannot find its way out of the openings 6—4. When the inner ends of the gates 5 are in abutment with the stops 8, as aforesaid, the latch mechanism 18 on the lever 16 is engaged with the seat 25. It is 85 possible, however, to swing the lever into dotted line position of Figure 1, the latch mechanism 18 being engaged in the seat 26. The links 19 and 21, then, will move the gates 5 until the openings 6 in the gates register 90 with the openings 4 in the bottom 2 of the flume 1. The water in the flume then will run out through the registering openings 5 and 6. The gates 5 may be as long as can be manipulated readily, and one man can 95 handle a long section of flume, because all that he will be called upon to do is to move some one lever 16 to another, a long section of flume being opened each time that one of the levers 16 is swung into proper direction.

The water flowing through the flume 1 from one end of the flume toward the other, has a tendency to move both of the gates 5 in the same direction, longitudinally of the flume, but because the gates are connected to the lever 16 on opposite sides of its fulcrum 17, the drag of the flowing water on one gate is made to offset the drag of the flowing water on the other gate, and the gates can 110 be shifted easily by means of the lever 16. The pivoted links 21 and 19 make such a

construction possible, and a gate having a straight line sliding movement cannot be operated in a satisfactory way if it is connected directly to a lever. The lever 16, furthermore, in connection with the links 19 and 21, is of advantage, since thereby, two gates may be worked from one operating element, with a corresponding saving of time and of the materials of construction. Because the 10 part 10 of the flume is imperforate, it is stronger than it would be if it had holes in it, and because the part 10 thus is strengthened it makes a secure place of mounting for the standard 11. Because the portion 10 of 15 the bottom of the flume is imperforate, it is not necessary to have gates working over it, and the gates, therefore, do not have to be fitted around the base of the standard 11.

What is claimed is:—

- 20 1. In a device of the class described, a flume comprising a bottom and sides, the bottom having perforated areas and an imperforate portion between the perforated areas, perforated gates slideable on the bottom to closed and opened positions with respect to the perforated areas, a standard mounted on the imperforate portion of the bottom, a lever, a fulcrum connecting the lever intermediate its ends with the standard, latch 25 mechanism on the lever and adapted to cooperate with the standard to hold the lever in adjusted positions, and oppositely extended links having their inner ends pivoted to the lever on opposite sides of the fulcrum,

the outer ends of the links being pivotally connected with the gates. 35

2. In a device of the class described, a flume comprising a bottom and sides, the bottom having perforated areas, and an imperforate portion between the perforated areas, 40 there being stops on the bottom between the imperforate portion and the perforated areas, perforated gates slideable on the bottom into engagement with the stops, thereby to dispose the gates in closed relation to the 45 perforated areas, a lever disposed above the imperforate portion of the bottom, a fulcrum for the lever, and oppositely extended links having their inner ends pivoted to the lever 50 on opposite sides of the fulcrum, the outer ends of the links being pivotally connected to the gates.

3. In a device of the class described, a flume comprising a bottom and sides, the bottom having perforated areas and an imperforate portion therebetween, perforated gates slideable on the bottom to closed and opened 55 positions with respect to the perforated areas, oppositely extended links having their outer ends pivoted to the gates, and means under the control of an operator and mounted on the imperforate portion of the bottom and connected to the inner ends of the links 60 for operating the links and for sliding the gates to opened and closed positions. 65

In testimony that I claim the foregoing as my own, I have hereto affixed by signature.

REUBEN HOWARD EVES.
